UNITED STATES PATENT OFFICE.

HERMAN KAESTNER, OF CUDAHY, WISCONSIN.

BULGE-HOOP FOR BARRELS.

1,014,005.

Specification of Letters Patent. Patented Jan. 9, 1912.

Application filed October 25, 1909. Serial No. 524,352.

To all whom it may concern:

Be it known that I, HERMAN KAESTNER, a citizen of the United States, residing at Cudahy, county of Milwaukee, and State of Wisconsin, have invented new and useful Improvements in Bulge-Hoops for Barrels, of which the following is a specification.

My invention relates to improvements in bulge hoops for barrels.

10 The objects of my invention are to provide a barrel with bulge hoops which will have cylindrical metal outer surfaces, extending beyond the central bulge of the barrel, so that the barrel may be rolled upon 15 the hoops, and a series of barrels may be piled with the bulge hoops of one resting upon the bulge hoops of the next whereby stability is secured in the pile, and the weight of the pile is sustained primarily by 20 the hoops.

In the following description, reference is had to the accompanying drawings, in which—

Figure 1 is a sectional view of a barrel 25 embodying my invention. Fig. 2 is a side view of the same. Fig. 3 is a detail sectional view enlarged, of a portion of one stave and two bulge hoops in cross section. Fig. 4 is a detail side view of a portion of 30 one of the hoops at the joint.

Like parts are identified by the same reference characters throughout the several views.

The barrel A is provided with ordinary 35 hoops B near each end. The inner bulge hoops, however, comprises cylindrical metal hoops C, having their ends permanently riveted together and inclosing wooden filling members D, which have their ends beveled 40 and lapped as in an ordinary hoop, but the ends are unconnected with each other and the wooden members D are unconnected with the metal hoops or members C. The metal hoops C, substantially inclose the 45 members D and extend inwardly beyond them preferably with a slight taper at e, and a slight expansion at the margin e', which bears upon the barrel as shown. I therefore secure a binding frictional contact 50 of both the wooden and the metal members upon the surface of the barrel. With this construction, there will be no shoulder at the inner margin, which can be struck accidentally and the hoop driven off, for this 55 shoulder will be no higher than that of any ordinary metallic hoop. The part of the

hoop which encircles the wooden member, will, however, be sufficiently distant from the surface of the barrel to project beyond the bulge at the center, and permit the barrel to roll on these hoops, or to be supported in a pile on such hoops.

The outer bulge hoops, if used, have inner wooden members F, which correspond with the members D in all respects. But the 65 outer members G (the metal portions of these hoops) merely cover the wooden portions without extending inwardly from them. Both the wooden members F and the metal members G may be arranged to 70 abut the members D of the inner bulge hoops, as shown.

In adjusting these bulge hoops in position, the wooden hoop will be first adjusted about the barrel, nearer to the end than the position to be finally occupied. The metal hoop is then adjusted to the wooden hoop on the lower side and the upper side pushed inwardly over the meeting ends of the wooden hoop, the latter drawing together during 80 this operation. The two members may then be driven inwardly to a binding position.

The wooden hoop being unconnected at its ends, is expanded by the wedging action 85 of the barrel into binding pressure against the metal hoop, the wooden hoop serving only as a filler, and the entire strain being exerted on the metal. This prevents the metal hoop from knocking off. By extending 90 the metal hoop beyond the wooden hoop into contact with the barrel, I not only secure a binding frictional contact between the metal hoop and the staves, but also eliminate the abrupt high shoulder which is 95 ordinarily presented by combination bulge hoops, and which has heretofore prevented the successful introduction of such hoops, owing to the tendency of both the metal and the wooden hoop to recede together when 100 struck forcibly on such shoulder. By expanding the edge margin of the metal hoop, it is prevented from cutting into the staves when driven on.

Having thus described my invention, what 105 I claim as new, and desire to secure by Letters Patent is,—

1. A barrel provided with a bulge hoop on each side of its central portion, each comprising a wooden member and a flat metal 110 band covering substantially the whole outer surface of the wooden member, said hoops

being of such thickness that the metal bands 5 may support the barrel horizontally from a flat surface; each of said metal bands being wider than the wooden member, and ar-
ranged to extend therefrom toward the central bulge portion of the barrel and into en-
gagement with the surface of the barrel at a
distance from the wooden member, and sub-
stantially at the same distance from the
10 longitudinal center line of the barrel as the
outer surface of the wooden member, with-
out forming an abrupt shoulder at the inner
margin of the hoop of sufficient height to
permit the hoop to be driven off by acci-
15 dental impacts.

2. A bulge hoop for barrels comprising a wooden hoop member, having its ends bevel-
eled and lapped upon each other and un-

connected, in combination with a metallic hoop inclosing the wooden hoop, and having 20 its ends riveted together, the inner margin of the metallic hoop extending beyond the wooden hoop and bearing upon the surface of the barrel and expanded along its edge, in substantial conformity to its tapered sur- 25 face, together with a second bulge hoop having a similar wooden member, and a metallic hoop of substantially the same width as the wooden member.

In testimony whereof I affix my signature 30 in the presence of two witnesses.

HERMAN KAESTNER.
